UNITED STATES PATENT OFFICE.

SIMEON F. PIERCE, OF ST. PAUL, MINNESOTA.

BOILER-FURNACE.

SPECIFICATION forming part of Letters Patent No. 784,880, dated March 14, 1905.

Application filed June 17, 1904. Serial No. 212,940.

To all whom it may concern:

Be it known that I, SIMEON F. PIERCE, a citizen of the United States, residing at St. Paul, in the county of Ramsey and State of Minnesota, have invented certain new and useful Improvements in Boiler-Furnaces, of which the following is a specification.

My invention relates to improvements in boiler-furnaces of the class wherein part or all of the fuel is first coked before being fed to the main grate; and its object is to provide improved means for leading the smoke and gases generated in the coking-chamber to the main grate-bars, for introducing heated air to the fire-box, and for supporting, strengthening, and preserving the inner wall of the coking-chamber.

To this end my invention consists in the features of construction, combination, and arrangement of parts hereinafter described and claimed.

In the accompanying drawings, forming part of this specification, Figure 1 is a view, partly in front elevation and partly in section, on line *w w* of Fig. 2 of a furnace embodying my improvements. Fig. 2 is a vertical section on line *x x* of Fig. 1. Fig. 3 is a horizontal section on line *y y* of Fig. 1. Fig. 4 is a view, partly in front elevation and partly in section, on line *w' w'* of Fig. 6, showing a modified arrangement of air-inlet pipes. Fig. 5 is a vertical section on line *x' x'* of Fig. 4, and Fig. 6 is a horizontal section on line *y' y'* of Fig. 4.

In the drawings, A represents the masonry side walls, B the front wall, and C the bridge-wall, of a furnace in which is seated a boiler D. At the bottom of the structure is an ash-pit 2, above which are the main grate-bars 3 and fire-box 4. In the front wall are the doors 5 and 6 of the main ash-pit and fire-box, respectively, and the doors 7 and 8 of the coking-chamber and its ash-pit, respectively.

On each side of the fire-box and along the side wall of the furnace is a coking-chamber E, extending, preferably, from the front wall of the furnace to the bridge-wall. The side and front walls A and B of the furnace thus constitute the outer side and front walls, respectively, of the coking-chamber, and when 50 the coking-chamber extends back to the

bridge-wall, as shown in the drawings, the bridge-wall will constitute the rear wall of the coking-chamber. At the bottom of the coking-chamber is an endless-chain grate F and below it is an ash-pit 9, having its floor raised 55 above the floor of the furnace to allow room beneath it for the passage 10, hereinafter described. The inner side wall of the coking-chamber—that is, the wall dividing the coking-chamber and its ash-pit from the main fire-box 60 and ash-pit of the furnace—comprises a lower upright portion 11 and an arched upper portion 12, extending over the top of the coking-chamber to the side wall of the furnace, which supports the upper end thereof. The wall of 65 the coking-chamber is formed just above the level of the main grate 3 with a longitudinal opening 13, through which the coked fuel passes or is carried out of the coking-chamber onto the main grate. 70

In order to accomplish the complete discharge of the coke from the coking-chamber to the main grate, as well as to provide a convenient and easily-operated means for regulating the discharge, I have provided and endless-chain grate F, composed of pivoted links 14, passing over interspaced drums 15, square in section, keyed to shafts 16, journaled in suitable bearings, such as the bearings 17 at the rear of the bridge-wall and 18 in the front wall of 80 the furnace. These drums may be operated by means of a crank 19, rotatably supported upon a pin 20 on the front wall of the furnace, through the medium of intermeshing gears 21 upon the crank and 22 upon the end of one of the 85 shafts 16. In order to operate the grate easily and slowly, the gear upon the drum-shaft is made considerably larger than the gear upon the crank. In order that the grate may present a substantially horizontal surface as well 90 near the side walls of the coking-chamber as midway between those walls, the outer wall and the inner wall may be cut away or recessed at 23 and 24, respectively, as shown in the drawings. 95

If the smoke and gases generated in the coking-chamber were led to the main grate directly or through highly-heated passages, they would reach the grate in so heated a condition as soon to destroy it, particularly if 100

they were discharged into the ash-pit below it. It is therefore important that the passages should be so situated and of such length as to allow the gases to cool during their passage 5 therethrough, and it is also important that the passages should be constructed and arranged in such way that their walls shall not be destroyed by the heat of the furnace. To accomplish these results, I have provided a passage 10 15 20 sage 25, inset deeply within the outer side wall A of the furnace and extending from the top of the coking-chamber down to the bottom of the furnace. This passage communicates with the upper part of the coking-chamber by means of a branch passage 26 in the side wall A and with the ash-pit below the main grate by means of a passage 10, extending from the lower end of the passage 25 underneath the ash-pit of the coking-chamber 25 30 35 to the main ash-pit. These passages are preferably of a width from front to back nearly as great as the depth of the coking-chamber.

In order to supply heated air to the main fire-box to consume the products of combustion, as well as to cool the inner wall of the coking-chamber, and thus protect it from destruction under the intense heat on both sides of it, I lead the air through the interior of the inner side wall of the coking-chamber by 40 45 50 means of air-ducts in the wall communicating separately with the outside air and discharging into the fire-box at predetermined selected points. In order not only not to weaken the side wall, but positively to strengthen and support it, as well as to secure other structural and operating advantages, I make these ducts of metal pipe having support at one or both ends in the walls of the furnace. This may be done in various ways. In the form shown 55 60 65 in Figs. 4, 5, and 6 the pipes 27 are carried horizontally at different levels through the front wall B of the furnace and the inner side wall of the coking-chamber, each pipe having a separate inlet-opening 28 to the outside air and either discharging into the fire-box through a nozzle 29 in the side wall or extending entirely 70 75 80 through the side wall into the bridge-wall and formed therein with a return portion 30, discharging into the fire-box through a nozzle 31. I prefer, however, to arrange the pipes as shown in Figs. 1, 2, and 3, where pipes 32, having each a separate inlet-opening 33, are carried side by side through the side wall A of the furnace and downwardly through the 85 90 95 interior of the upper or arched portion 12 of the inner side wall of the coking-chamber. Some of the pipes may extend only part way down the inner side wall, discharging from the side wall into the fire-box through nozzles 95 100 105 110 115 120 125 130 135 140 145 150 155 160 165 170 175 wall of the coking - chamber. As the grate turns about the forward drum the coke will drop from the chain grate onto the main grate 3 of the furnace, and thus a constant supply 5 of coke may be fed to the fire. The supplying of the coke is facilitated by having the chain grate positioned so that its upper surface will stand at a higher level than the main grate 3, as shown in Fig. 1 of the drawings.

10 It is obvious that various modifications may be made in the details of the construction without departing from the principle of the invention, the scope of which is defined in the claims.

15 Having now described my invention, what I claim as new, and desire to secure by Letters Patent, is—

1. In a furnace of the class described the combination, with the walls and fire-box thereof, of a coking-chamber arranged at the side of the fire-box and having an inner side wall dividing it therefrom, pipes supported at one end in one of the walls of the furnace and extending through the interior of the inner side 25 wall of the coking-chamber, each pipe leading separately from the outside air and discharging into the fire-box at a predetermined point, and a passage within one of the walls of the furnace and along the bottom thereof 30 leading from the coking-chamber to the ash-pit below the main grate.

2. In a furnace of the class described, the combination, with the walls and fire-box thereof, of a coking-chamber arranged at the side 35 of the fire-box and having an inner side wall dividing it from the fire-box, and pipes supported at one end in one of the walls of the furnace and extending through the interior of the inner side wall of the coking-chamber, each 40 pipe leading separately from the outside air and discharging into the fire-box at a predetermined point.

3. In a furnace of the class described, the combination, with the side wall and fire-box,

of a coking-chamber arranged at the side of 45 the fire-box and having an inner side wall dividing it therefrom, and pipes passing through the side wall of the furnace and extending downwardly through the interior of the inner side wall of the coking - chamber, said pipes 50 having separate air - inlet openings and discharging into the fire - box at predetermined points.

4. In a furnace of the class described the combination, with the front wall, side wall, 55 bridge-wall and fire-box, of a coking-chamber arranged at the side of the fire-box and having an inner side wall dividing it therefrom, a main pipe supported at its ends in the front and bridge walls and passing intermediately 60 through the interior of the inner side wall of the coking-chamber, said pipe extending into the bridge - wall and discharging therefrom into the fire - box, and one or more communicating pipes passing through the side wall 65 of the furnace and extending downwardly through the interior of the inner side wall of the coking-chamber to the main pipe.

5. In a furnace of the class described the combination, with the fire - box, main grate 70 and side wall, of a coking-chamber arranged at the side of the fire-box and having a dividing-wall extending over the chamber to the side wall of the furnace, the dividing-wall being formed with an opening above the main 75 grate, and one or more pipes passing through the side wall of the furnace and extending down along the inner side of the dividing-wall and through the opening therein in supporting proximity to the dividing-wall, said pipes 80 being open at both ends, for the purpose set forth.

In testimony whereof I affix my signature in presence of two witnesses.

SIMEON F. PIERCE.
